UNITED STATES PATENT OFFICE.

WALTER F. HEROLD, OF NEWARK, NEW JERSEY, ASSIGNEE TO THE BASSICK COMPANY, OF BRIDGEPORT, CONNECTICUT, A CORPORATION OF CONNECTICUT.

CASTER.

Application filed July 5, 1923. Serial No. 649,467.

To all whom it may concern:

Be it known that I, WALTER F. HEROLD, a citizen of the United States, and resident of Newark, in the county of Essex and State 5 of New Jersey, have invented certain new and useful Improvements in Casters, of which the following is a specification.

The invention relates to casters and particularly to a construction of spring frame 10 or socket, and coacting parts, for use in connection with metal or other hollow legs of beds or other furniture.

In the usual spring frame as now used a transverse top portion of rectangular shape 15 is provided, through an opening in which the pintle extends, the frame having spring arms extending downwardly from the top portion on opposite sides. A difficulty is apparent when this type of frame is used with the 20 smaller sizes of caster, namely, that so little space is provided between the sides of the rectangular transverse top portion of the frame that a small pintle only can be used, or if a pintle of larger diameter is used, the 25 top frame portion will be unduly weakened by the comparatively large opening through which the pintle extends.

One of the objects of my invention is the provision of a spring frame the top portion 30 of which is formed with a more or less circular, or polygonal, shape, so that a larger opening, and hence a larger pintle, may be used in the smaller sizes of caster, while leaving ample room between the edge of the 35 opening and the outer edges of the top transverse portion of the frame. Another object of the invention is the provision of a spring frame or socket member of novel and improved form, which may be manufactured 40 economically and which will be particularly effective in operation. In this construction the downwardly extending arms of the frame comprise pairs of strips crossing each other at an angle, so that the bottom outer 45 edge of one strip will lie more or less under the upper outer edge of the other strip of the pair. With this arrangement the frame or socket may readily be pushed into position 50 within a hollow leg, the spring arms pressing against the interior thereof. Force 55 acting to withdraw the frame from the leg will cause the lower end portions of the crossed arms or strips to tend to spread apart and thus to engage more tightly against the interior of the leg. This is so because of the

fact that the downwardly extending arms are inclined to the axis of the leg, so that the friction of the inner surface of the leg against the outer surface of an arm, when force is exerted to withdraw the frame, with 60 a straight pull, will act at an angle to the length of the arm and hence will tend to cam it outward.

With such a construction the frame may 65 economically be formed from a single rectangular blank without cutting out or waste of any material. The construction may be used as a pintle frame with the pintle extending through an opening in the upper 70 transverse portion of the frame in which case the manner in which the downwardly extending arms are bent will give a roughly circular form to the top transverse portion of the frame with the advantage noted above. The construction is not, however, 75 limited in its usefulness to this form of caster, and may, for example, be used as a socket which is intended to be pushed into position within a hollow leg or the like, in 80 which it is intended to remain permanently.

Other objects of the invention comprise the provision of various elements of construction and combinations of parts, all as will be more fully described in the accompanying specification.

In order that the invention may be more clearly understood attention is hereby directed to the accompanying drawings forming part of this application, and illustrating one embodiment of the invention. In the 90 drawings

Fig. 1 represents a side elevation of a 95 caster embodying the invention mounted in position within a hollow leg shown in section;

Fig. 2 is a corresponding front elevation of the same, the legmount of the caster and top transverse portion of the spring frame being shown in section; and

Figs. 3 and 4 are horizontal sections taken 100 respectively on lines 3—3 and 4—4 of Fig. 1.

Referring to the drawings, the caster as illustrated comprises the usual horn 1, carrying a caster wheel 2, the horn having a transverse top portion 3 to which is secured the 105 pintle 4 to extend upwardly therefrom. A leg supporting disc and legmount 5 is illustrated as being carried by the pintle and mounted upon the shoulder 6 at the lower end thereof.

The spring frame comprises a transverse top portion 7 having an axial opening therethrough through which extends pintle 4, the upper end of the pintle being upset or provided with lugs 8 in any usual way to prevent the frame from slipping off of the upper end of the pintle.

The spring frame is provided with downwardly extending arms which are bent to 10 extend at an inclination to the vertical axis of the spring frame, or to the vertical axis of the hollow leg in which the frame is to be inserted. As shown, the downwardly extending arms of the frame preferably comprise pairs of strips, one of which crosses the other at an angle, and each of which crosses the vertical axis of the frame at an angle. Thus, as is shown in the drawings, the downwardly extending portion of the frame at one side comprises a pair of strips 9, 10, while the downwardly extending portion of the frame on the opposite side comprises a pair of strips 9¹, 10¹, the strip 9 being bent to extend over the strip 10 and the strip 9¹ correspondingly to extend over the strip 10¹. The downwardly extending portion of the frame comprising strips 9 and 10 is diametrically opposite to the portion comprising strips 9¹ and 10¹, strips 9 and 9¹ crossing the vertical axis of the frame in one direction, approximately parallel to each other, while strips 10 and 10¹ cross the vertical axis in the other direction, approximately parallel to each other. 30 The frame is bent to shape out of suitable spring metal and when the caster is operatively positioned by pushing the frame and pintle into a hollow leg 11 the strips 9, 9¹, and portions of the strips 10 and 10¹, will 40 press outwardly against the interior of the leg to hold the caster frictionally in position. The legmount 5 is illustrated as being used, although its use is not essential to the invention, and with this construction the lower ends of the spring strips will be confined by the vertical flange of the legmount when the caster is not positioned within a leg.

It will be noted that the adjacent downwardly extending portions of the frame, such as portions 9 and 10, are bent downwardly from the top transverse portion 7 in such a way that the top edge of the same, that is the intersection of the downwardly extending portions 9 and 10 with the plane of the top portion 7, will form a curve approximating a semi-circle, the same being also true in regard to the opposite arms 9¹ and 10¹, the intersection of which with the top transverse portion 7 roughly forms a semi-circle. Accordingly, a larger opening for the pintle through the top portion 7 of the frame may be provided, in the smaller sizes of caster, than could safely be provided, if the top transverse portion of the

frame were formed as the usual rectangle. This is so, because with the construction described the metal of the top transverse frame portion surrounding the pintle opening will approximately form an annulus 70 and the edge of the pintle opening will nowhere be as close to the outside edge of the top transverse portion as it would be if the top portion were rectangular, where the distance from the pintle opening to the adjacent side edge would necessarily be less than in the construction described.

The construction may readily and economically be formed from a single rectangular strip of sheet metal by slitting the metal 80 back a distance from the two ends of the rectangle, parallel to the side edges, bending the blank to cause the two end portions to extend downwardly on opposite sides from the intermediate portion, which latter portion is not slitted and is intended to form the top portion 7 of the frame, and then bending the portions of the slitted downwardly extending arms in opposite directions so as to cause each of the same to cross the other in the manner shown in the drawings. This operation may be so performed as to give the top portion of the frame the approximately circular or polygonal form referred to.

The amount of lateral bending to be given the side arms of the spring frame may be determined more or less by experiment. It may, however, very suitably be such as is shown in the drawings in which the lower ends of a pair of arms which approach each other at the bottom, such as the arms 9¹ and 10, will not quite meet when the caster is in its operative position, as shown in Fig. 1, the adjacent bottom edges of the opposite pair of arms, 9 and 10¹, also coming almost into engagement with each other at the opposite side of the frame.

When the frame is pushed into a hollow leg, as shown, the top transverse portion 7 of the frame will approximately fit within the interior of the leg, and will form a rigid strut to center the upper end of the pintle and prevent more than a very slight tilting of the same in any direction. The outer surfaces of the spring arms will frictionally engage and bear against the inner surface of the leg throughout the greater part of the lengths of the outermost arms 9, 9¹, and at the upper and lower portions of the undermost arms 10 and 10¹. When force acts on the caster to withdraw the same from the leg, as when the leg is lifted and the caster is to be withdrawn by a straight pull, or when the leg is raised and the weight of the caster creates a downwardly extending force, the friction exerted by the outer surfaces of the spring arms against the inner surface of the leg will, of course, be a vertical upwardly reacting force. Since the

spring arms all cross the vertical at an inclination the result of such force will be to tend to move the lower ends of the arms 9 and 10 further away from each other and 5 the same in regard to the lower ends of the arms 9¹ and 10¹. Moving the lower ends of each pair of arms further away from each other laterally tends, of course, to press them more firmly into engagement with the 10 inner surface of the leg. It is, therefore, apparent that force acting to withdraw the frame from the leg tends to cause the frame to bind more tightly within the leg. In the case of a frame which is intended to be 15 withdrawn from the leg at intervals, such as the spring frame of a removable caster, such as that shown in the drawings, the frame should of course not bind so tightly as to prevent such withdrawal. With a 20 spring frame having properly proportioned arms similar to that shown in the drawings, the result of the action referred to will be to cause the frame to hold firmly in position but to enable the same to be withdrawn 25 by a moderate pull.

It will be noted that, in the form of the invention shown in the drawings, each arm or strip of the frame, such as 9, is bent laterally to extend across the vertical axis 30 of the frame in one direction, at an angle to said axis, while the other arm or strip of the coacting pair of arms, such as the strip 10, extends across the axis from the opposite side thereof, at a similar angle thereto. The 35 arms also of course extend laterally at an angle across vertical elements of the inner surface of the leg. The outer surfaces of the arms being preferably somewhat curved laterally, as stated, at least adjacent the 40 upper edges thereof, these outer surfaces will engage against the inner surface of the leg, and the spreading apart of the lower ends of the strips of each pair of arms, caused by a downward pull on the caster, 45 will press the outer side edges of the lower ends of the arms more firmly against the inner surface of the leg. It should also be noted that the crossing of one arm over the other, in the form of construction shown, 50 stiffens and reinforces the spring arms.

It should be understood that the invention is not limited strictly to the details of construction which have been particularly illustrated and described but that the same 55 is of considerable breadth, as is indicated by the accompanying claims.

What I claim is:

1. In a caster, a spring frame, adapted to 60 be inserted within an opening in a leg, comprising a transverse top portion and downwardly extending arms, each arm comprising a pair of strips, one inside the other, one strip of each pair being bent laterally to extend across the other, at an angle thereto.

2. In a caster, a spring frame, adapted to

be inserted within a round hollow leg of uniform section, comprising a transverse top portion of approximately circular shape and downwardly extending spring arms adapted to press against the interior surface of the leg throughout the greater portions of their length, and bent to extend across vertical elements of said surface at inclinations thereto, certain of said arms crossing over and lying against others thereof. 70

3. In a caster, a spring frame, adapted to be inserted within an opening in a leg, comprising a transverse top portion of approximately circular shape, and downwardly extending spring arms, adapted to press against the interior surface of the leg at various points thereon, said arms being bent laterally to extend across vertical elements of said surface at inclinations thereto, certain of said arms crossing over and lying against others thereof. 80

4. In a caster, a spring frame, adapted to be inserted within an opening in a leg, comprising a transverse top portion and downwardly extending arms comprising a pair of strips on one side and a similar pair of strips on the opposite side, each pair comprising a strip bent laterally to extend at an inclination across the vertical axis of the frame from one side thereof to the other, and another strip inside the first, bent laterally to extend at an inclination across the vertical axis of the frame, from the second mentioned side thereof to the first mentioned side thereof. 90

5. In a caster, a spring frame adapted to be inserted within a hollow leg, comprising a transverse top portion and integral arms extending downwardly on opposite sides thereof, comprising pairs of strips, one bent to extend over the other at an inclination to the vertical and the other bent to extend at the inner side of the first at the opposite inclination, the lower ends of said strips occupying approximately the periphery of a circle, with the lower ends of certain arms brought close to, but out of contact with, each other. 95

6. In a caster, the combination of a caster horn and pintle extending upwardly therefrom, and a spring frame having a transverse top portion with a central opening therethrough, through which said pintle extends, the edge of said top portion being shaped so that all edge portions thereof are approximately equidistant from said opening, said frame having spring arms extending downwardly from said edge, adapted to press against the interior surface of a hollow leg in which the frame is inserted, and bent laterally at an angle. 105

7. In a caster, the combination of a caster horn and pintle extending upwardly therefrom, and a spring frame having a transverse top portion with a central opening 110

therethrough through which said pintle extends, and having downwardly extending arms comprising a pair of strips on one side and a similar pair of strips on the opposite side, each pair comprising a strip bent laterally to extend at an inclination across the vertical axis of the frame from one side thereof to the other, and another strip inside

the first, bent laterally to extend at an inclination across the vertical axis of the frame, from the second mentioned side thereof to the first mentioned side thereof.

In testimony whereof I have signed my name to this specification.

WALTER F. HEROLD.
